UNITED STATES PATENT OFFICE

KARL MAYBACH, OF FRIEDRICHSHAFEN, GERMANY, ASSIGNOR TO MAYBACH-MOTOR-ENBAU GESELLSCHAFT MIT BESCHRAENKTER HAFTUNG, OF FRIEDRICHSHAFEN, GERMANY

CARBURETOR

Application filed September 20, 1927, Serial No. 220,712, and in Germany October 4, 1926.

My invention relates to carburetors of internal combustion engines and has special reference to carburetors having a spraying nozzle.

5 With these carburetors it is usual to regulate the amount of entering air by means of an air valve or butterfly disc, to regulate the amount of fuel by means of a needle valve or the like, and to regulate the quantity of the 10 mixture admitted to the engine by means of a throttle valve or disc.

One main object of my invention is improvement of this regulating mechanism, so as to be able to do without this throttle valve 15 for regulating the mixture.

Another main object is the exact and easy regulation of the amount of entering fuel.

A further object of my invention is to provide for simple and easily operated means for 20 changing the richness of the mixture.

There are other advantages connected with the carburetor constructed in accordance with my invention which will be pointed out later.

For the purpose of avoiding the throttle 25 valve for controlling the mixture I remove the air valve so as to be close to the spraying nozzle. According to my invention the spraying nozzle which for example may consist of a tube arranged in the direction of 30 the entering air, is surrounded by an air controlling mechanism. This means that the amount of air and the amount of fuel both are regulated at the spot where they meet. Thus it is not necessary to have a third regulating mechanism for the mixture. Of course 35 special devices have to be provided to make this arrangement as effective as possible.

My invention is explained best by having 40 reference to the accompanying drawings.

Fig. 1 is a longitudinal vertical middle section through a carburetor in a more or less diagrammatical manner.

Fig. 2 is a detailed view on the nozzle tube 45 of Fig. 1, but seen in a plane at right angles to the plane of Fig. 1.

Fig. 3 is a sectional view on the air intake mechanism taken on line 3-3 of Fig. 1 looking to the right hand side; it represents a 50 special position of the wing mechanism.

Fig. 4 is a cross section through the upper wing 12 taken on line 4-4 of Fig. 1.

Referring to Fig. 1, arrows A indicate the air flow, arrow G shows the flow of the gasoline, and arrow M indicates where the mixture flows to the engine. The engine has flanges E to which the carburetor is fastened in any well known manner.

The amount of air entering the engine is regulated by the distance between lower wing 11 and upper wing 12. These wings may swing around pins 13. In Fig. 1 they are represented in open position; the closed position is shown in dotted lines. Two toothed segments 14 serve for transmitting movement 65 from one wing to the other. The inner wing portions have recesses 15 into which the nozzle tube 16 extends when the wings are in closed position. A small opening 17 is provided which allows for a very small amount 70 of air to pass even in closed position of the wings.

Nozzle tube 16 at its end has two oppositely arranged holes 18 which are of pear-like shape having their pointed ends towards the engine. Outer tube 19 closely fitting over tube 16 is pressed in the left hand direction by means of spring 20 and is held in position against this spring action by the pressure resulting from lever 21. This lever may swing around pin 22 journaled in the end of rod 23.

The fuel which may be gasoline comes from a float chamber 24 which in detail may be constructed in any well known manner. In 85 the example represented the gasoline flows in at 25 passing a float valve 26 operated by float 27. It then fills the chamber 24 up to level 28 from which the air passing through the opening between the wings 11 and 12 90 sucks the fuel through tube 16 and through holes 18.

The whole mechanism is operated by moving lever 29. If this lever which is journaled in pin 30 is moved in the direction of arrow C 95 the carburetor is closed. By means of lever 31 revolving together with lever 29 around pin 30 and being in fixed relation to lever 29 rod 32 pulls lever 33 so as to revolve around pin 13. Lever 33 is in fixed relation to wing 11 100

and causes this wing to swing inwardly with regard to the air intake, and wing 11 by means of toothed segments 14 makes wing 12 also swing inwardly. Lever 29 is connected with cam 34 against which the free end of lever 21 is pressed. Moving lever 29 in the direction of arrow C means adequate turning of cam 34 so that spring 20 by its pressure will move lever 21 in the left hand direction and at the same time tube 19 is shifted over tube 16 so that holes 18 are partly or totally covered, depending on the amount of movement of lever 29.

By means of a thread 35 and a nut 36 rod 23 may be set in its longitudinal direction to such a position as may be thought adequate with regard to the lever and cam arrangement regulating the fuel access.

In Fig. 2 it is shown how the tube 19 may be slotted so as to give a perfect fitting over tube 16.

From Fig. 3 a special arrangement of the air intake wings may be seen in its effect. When opening the wings from the closed position at first only a middle portion of the total cross section is opened as may be seen from Fig. 3. This middle portion is situated exactly around nozzle tube 16. By this arrangement a perfect carburation is attained even at low speed of the motor because the vacuum around the nozzle is always sufficient to suck an adequate amount of gasoline due to the comparatively high speed of the air passing by the nozzle.

This arrangement consists in the following:

The side portions 40 of upper wing 12 are cut off and are loosely journaled at 13. They have apertures 41 into which arms or bolts 41' extend which are in rigid connection with main and middle wing portion 12. Fixed to this middle portion is a crosspiece 42 which extends over the side portions 40 and in which springs 43 are arranged. These springs 45 press against bolts 44 which again press down the side wing portions 40.

Thus, when the wings are opened at first the side portions 40 do not move upwardly but the pressure of springs 43 causes them to be pressed against the downwardly moving lower wing 11. Only the middle portion 12 moves upwardly so that only the middle cross section of the air intake opens. Side portions 40 are so long following the downward movement of wing 11 against which they are pressed until arms 41' bear against the upper edge of apertures 41. Thereafter these arms 41' are taking the side portions with the middle portion in its upward movement.

When closing the wings the effect of this arrangement will be the same. Side portions 40 will first touch the lower wing 11 and close the outer portion of the air intake leaving open only the middle portion. This is then

closed by subsequent movement of the lever arrangement against the pressure of springs 43.

I do not want to be limited to the details described or shown in the drawings because many variations will occur to those skilled in the art.

What I claim is:

1. A carburetor for internal combustion engines comprising a fuel nozzle; a mixing chamber; and an air regulating mechanism; said fuel nozzle and said regulating mechanism being situated closely to each other; said regulating mechanism comprising two wings adapted on adequate movement to open and close said mixing chamber, one of said wings being subdivided into middle and side portions, and means for allowing the side portions to open later than the middle portion.

2. A carburetor for internal combustion engines comprising a fuel nozzle; a mixing chamber; and an air regulating mechanism; said fuel nozzle and said regulating mechanism being situated closely to each other; said regulating mechanism comprising two wings adapted on adequate movement to open and close said mixing chamber, one of said wings being subdivided into middle and side portions, and means for allowing the side portions to close earlier than the middle portion.

3. A carburetor for internal combustion engines comprising a fuel nozzle; a mixing chamber; and an air regulating mechanism; said fuel nozzle and said regulating mechanism being situated closely to each other; said regulating mechanism comprising two wings adapted on adequate movement to open and close said mixing chamber, one of said wings being subdivided into middle and side portions, and means for allowing the side portions to open later and to close earlier than the middle portion.

4. A carburetor for internal combustion engines comprising a fuel nozzle; a mixing chamber; an air regulating mechanism; said fuel nozzle and said regulating mechanism being situated closely to each other; said regulating mechanism comprising two wings adapted on adequate movement to open and close said mixing chamber, one of said wings being subdivided into middle and side portions, and means for allowing the side portions to open later and to close earlier than the middle portion; said fuel nozzle comprising an inner tube having a hole in its side wall, an outer tube fitting over said inner tube and means for shifting said outer tube on said inner tube; and means for operating said air regulating mechanism, said operating means and said tube shifting means being connected to each other so as to operate simultaneously.

KARL MAYBACH. 130
